UNITED STATES PATENT OFFICE.

ALEXANDER W. MESTON, OF ST. LOUIS, MISSOURI.

DESIGN FOR A FRAME FOR ELECTRIC MOTORS.

SPECIFICATION forming part of Design No. 22,277, dated March 7, 1893.

Application filed August 30, 1892. Serial No. 444,579. Term of patent 7 years.

To all whom it may concern:

Be it known that I, ALEXANDER W. MESTON, a citizen of the United States, residing at St. Louis, in the State of Missouri, have invented 5 and produced a new and original Design for a Frame for Electric Motors, of which the following is a full, clear, and exact description, reference being had to the accompanying drawing, wherein the figure represented is a 10 view in side elevation of my original design.

The design consists, essentially, in a cylindrically shaped casing for electric motors mounted upon a tripod base, as is shown.

In the drawing, A indicates the cylindrical 15 shaped motor casing or body portion, and a, bands or beads on the ends of the same. Near the outer edge of the flat faces of the ends, are convexed beads b in the form of a quadrant, which beads terminate in a step c and 20 a concavo bead d. Projecting from the bead d is a converging portion e whose outer converging ends f are curved gently inward, until the curve meets the flat face, which face is interrupted by a concavo bead g concentric 25 therewith. Toward the center of the flat face of the projecting portion e, the frame is again curved gently outward to form the step h, when from said steps, projects the parallel sides of centrally located hubs, which have 30 flat end faces and beveled corners, as shown.

All the parts before mentioned, are circular and arranged concentric with each other, and the shape of each end of the frame, is substantially the same. The base upon which this cylindrically shaped frame is mounted, is what 35 is known as a tripod, that is, the bottom portion i is hemispherical in shape, and has projecting therefrom, three legs, j, j', &c., rounded on their upper sides, and terminating in semi-elliptically shaped feet, k, k', &c., these legs 40 being equi-distantly placed and radially disposed around the rounded surface of the hemispherically shaped base. Extending from the top of this base, is a tapering column or standard B, the top of which terminates in 45 a quirk molding l, from which extends a cap under the cylindrical body portion of the motor frame.

What I claim is—

The design for a motor frame, substantially 50 as herein shown and described.

In testimony whereof I affix my signature, in presence of two witnesses, this 18th day of August, 1892.

ALEXANDER W. MESTON.
